UNITED STATES PATENT OFFICE

BRUCE H. WALLACE, OF CLEVELAND, OHIO, ASSIGNOR OF ONE-HALF TO FRANK D. FERRIS, OF CLEVELAND, OHIO

SIGN APPARATUS

Application filed November 8, 1926. Serial No. 146,995.

The purpose of this invention has been to design certain novel sign apparatus especially useful in show windows, or on sign-boards, or in like places, for attracting attention to advertising matter, or constituting advertising matter itself.

The features of the invention which have been especially devised for its purposes involve the provision of means for readily 10 mounting a moving sign part upon a window or support, to facilitate its actuation by suitable motor operating device of any simple kind, and said moving part may be associated with a sign feature directly painted on the 15 window or other support, or it may be associated with a separate sign part also attached to the window, or supporting base, whatever it may be.

It is known that sign devices involving 20 moving parts, serve to attract attention better than stationary sign apparatus and owing to the movability feature and peculiar mounting feature of my invention, I find that it proves highly successful for the desired purpose, in practise.

In the accompanying drawings:—

Figure 1 is a front elevation of a window to which my sign apparatus is applied, the motor operating means being also depicted 30 at the upper right hand corner of the view.

Figure 2 is a vertical sectional view taken about on the line 2—2 of Figure 1.

Figure 3 is a view in elevation of a modified adaptation of the invention.

Figure 4 is a sectional view taken on about the line 4—4 of Figure 3.

Figure 5 is a similar sectional view taken about on the line 5—5 of Figure 3.

For a full understanding of the present 40 invention, reference may be had to the drawings, the figures of which are briefly described above, in conjunction with the following description that sets forth certain preferred embodiments of the invention, to which, however, I do not wish to be entirely confined in the carrying out of the principles of construction employed, except as required by the scope of the appended claims.

Referring to the drawings, and especially 50 to Figures 1 and 2, it is noted that 1 design-

nates a window which may be an ordinary show window of a store, the window-glass being supported in the framework 2 in quite the customary manner. At 3 there is noted as painted upon the window a sign feature consisting of a portion of the body of a rooster. A second sign part designated 4 and in the semblance of the head part of the rooster which is the figure being illustrated as a part of the sign apparatus, is also utilized.

The sign part 4 is intended to have movability in relation to the sign part 3 for which reason, it is preferably separate from the window but associated properly with the sign part 3 so that the whole makes up the sign or representation of the rooster, or whatever may be the figure intended to be used in the advertising.

As a convenient means for applying the movable sign part 4 to the window, I avail of a vacuum or suction cup 5 which will be pressed against the window upon that portion thereof carrying the relatively stationary sign part 3. The suction cup 5 is provided with a pivot member 6 suitably headed 70 and the movable sign part 4 is formed with a recess 7 intended to partially receive the cup 5 and permit the body of the movable sign part 4 to fit rather closely against the window or against the stationary sign part 3 which 75 may or may not be painted upon the window.

By reason of its pivotal mounting, the movable sign part 4 may be moved and for this purpose a string or cord 8 is attached to the movable sign part 4 at 9 and leads over a 80 guide pulley or wheel 10 to a motor 11. In this instance, the motor 11 comprises a vibrating or oscillating arm 11^a which is adapted to move back and forth as shown by dotted lines and thus raise and lower the movable sign 85 part 4. In the illustration used, the head of the rooster which is the movable sign part 4, will be given a movement by the motor resembling the ordinary feeding movement of the head of the bird in picking its food. Appropriate legends may be applied to the window 90 appertaining to articles; for instance, "Take your pick," this legend or a similar one having relation to the particular thing advertised, such as an article for sale.

In Figure 3, there is shown a modification in which the relatively stationary sign part of the sign apparatus designated 4^a is separate from the window instead of being painted thereon, as before described, being held in place by one or more suction cups 12, the head portion of which is inserted through an opening in the said sign part 4^a. In this construction, moreover, I utilize a special suction cup 13 shown in Figure 4 having the large pivot member 6^a acting in a similar capacity to the member 6, previously described, but additionally passing through an opening in the stationary part 4^a of the sign.

In this particular construction, the stationary part 4^a will also have a recess or depression 7^a, and the movable sign part 4^b of the modification will have the recess or depression 7^b fitting over the depression or recess 7^a. In other words, the parts 13, 7^a and 7^b have a sort of nested relation so that the sign parts may be mounted and moved close together. A relatively stationary sign part 4^a may be very slightly spaced from the movable sign part 4^b in the construction now described.

It is apparent that with the general plan of construction of my sign apparatus as above set forth, various features and signs may be employed that rather graphically depict a certain idea of sales value and an attractive moving sign apparatus is simply and cheaply provided in this way.

Having thus described my invention, what I claim as new and desire to secure by Letters Patent of the United States, is:

1. Movable sign apparatus, comprising a sign adapted for mounting on a show-window, part of said sign being stationary, a second part being movable relatively to the first part, said movable part having a recess therein, and a suction cup within the recess of the movable part having means for connecting the movable sign part to the support in a movable relation to the stationary sign part.

2. Movable sign apparatus, comprising a sign adapted for adjustable mounting on a support, part of said sign being stationary and having a recess therein, a second part movable relatively to the first part also having a recess nesting with the first named recess, a suction cup fitting in the recess on the stationary part having means associated therewith and constituting a pivotal connection between the movable sign part and the stationary sign part and adapted to attach the two operatively to the support upon which the sign apparatus may be mounted.

3. Movable sign apparatus comprising a relatively stationary sign part, a relatively movable sign part, one of said parts having a recess therein, and a suction cup fitting in said recess and having means connecting the movable sign part to the support in a movable re-

lation to the stationary sign part, said apparatus being adapted for mounting on the support without necessitating alteration of the latter.

4. Movable sign apparatus comprising a stationary sign part, suction cup devices attached thereto for applying the same to a support, a movable sign part and a suction cup having means associated therewith and constituting a pivotal connection between the movable sign part and the stationary sign part, and adapted to attach the two operatively to the support on which the sign apparatus may be mounted, said sign parts having nesting recesses in which the suction cup fits.

In testimony whereof I affix my signature.

BRUCE H. WALLACE.
